UNITED STATES PATENT OFFICE.

THOMAS P. CARSON, OF BRECKENRIDGE, TEXAS.

HYDRAULIC ELEVATOR.

1,412,920.

Specification of Letters Patent. Patented Apr. 18, 1922.

Application filed August 19, 1921. Serial No. 423,619.

To all whom it may concern:

Be it known that I, THOMAS P. CARSON, a citizen of the United States, residing at Breckenridge, in the county of Stephens 5 and State of Texas, have invented certain new and useful Improvements in Hydraulic Elevators; and I do hereby declare the following to be a full, clear, and exact description of the invention, such as will enable 10 others skilled in the art to which it appertains to make and use the same.

This invention relates to new and useful improvements in fluid elevators and more particularly to a device adapted to be used 15 for lifting or raising oil and other liquids from wells or pits, the main object of the present invention being the provision of a fluid elevator which is especially adapted for use in removing oils from wells where 20 the pressure of gas which is originally intermixed with the oils has reduced to such an extent that the oil discontinues to flow freely from the well.

It is a well known fact that as a general 25 rule after oil wells are drilled in, there is sufficient pressure of gas in the well or beneath the oil to carry the oil to the top of the earth making what is known as a gusher. After a continual flow for a period of time, 30 the pressure of gas in the well is reduced so that the pressure is not sufficient to carry the oil to the top of the well, thus necessitating the use of pumps or other means for extracting the oil from the well and as this 35 pumping or extracting the oil from the well is comparatively expensive, it is one of the features of my invention to provide means whereby the pressure of gas still remaining in the well can be utilized for raising or re- 40 moving the oil from the well at a comparatively small expense.

A further object of this invention is the provision of a device adapted to be lowered into the usual well casing of a fluid well and 45 so arranged that the slight pressure of gas remaining in the well will be caused to accumulate until the pressure is sufficient to carry the fluid to the top of the well through a reduced tubing inserted within the original casing.

With the above and other objects in view the invention consists in the novel features of construction, the combination and arrangements of parts hereinafter more fully 50 set forth, pointed out in the claims and

shown in the accompanying drawings in which:

Figure 1 is a longitudinal sectional view illustrating my invention in place within a well casing,

Figure 2 is an enlarged transverse sectional view taken on the line 2—2 of Figure 1,

Figure 3 is an enlarged transverse sectional view taken on the line 3—3 of Figure 1,

Figure 4 is a longitudinal sectional view taken through the plug or stop arranged within the casing to cause the accumulation of the gas pressure, and

Figure 5 is an enlarged longitudinal section taken through the guide which directs the oil into the reduced tube arranged within the original casing.

Referring now more particularly to the 75 drawings in which my invention is fully illustrated the numeral 1 designates the usual tubing or casing arranged within the well through which the oil originally flows after being drilled in and which also has 80 previously served as a guide for the tools in drilling the wells, said casing being closed at its upper end by means of the cap 2, which has an outlet pipe 3 communicating with one side thereof, provided with a valve 4 85 for the purpose of relieving the pressure of gas within the casing 1 when desired. After a well, known as a gusher has ceased to flow through the means of the original gas pressure, it generally necessitates the applica- 90 tion of a pump or other suitable means for removing the oil from the well and as the means in use at the present time and used heretofore has been so expensive that the profits of the oil have been reduced to a 95 minimum, it is the object of my invention to provide simple means adapted to be placed within the casing 1 of the well for removing the oil still remaining in the well, or afterward accumulating.

As the gas pressure in the well is not sufficient to carry the oil up through the original casing 1, a tubing generally indicated by the numeral 5 is inserted within the casing 1 so as to reduce the size of the outlet 100 whereby the pressure of gas which will be caused to accumulate within the casing 1 will be sufficient to carry the oil up through this tubing 5. This tubing 5 is inserted within the casing 1 and preferably extended 105 110

down to a point adjacent the lower end of the casing and provided at its lower end with a plurality of openings 6 whereby the oil will readily pass into the tubing. In order 5 to direct the oil and gas into the tubing 5 through the perforations 6, a hood 7 herein shown as in the form of an inverted truncated cone, is threaded on to the tubing, the larger end of the hood being slightly smaller 10 than the casing 1, so that the same can be readily inserted within the casing. From this it will be noted that the oil and gas pressure will be for the most part directed upwardly within the hood 7 and any gas or 15 oil not passing in through the openings 6 will be directed into the tubing 5 through the radial openings 8 formed in the tubing 5 adjacent the upper end of the hood. In order to reduce the flow of oil and gas upwardly through the tubing so as to create 20 a greater pressure, a nozzle member 9 is inserted within the tubing 5 at a point within the hood 7, it being preferred to have a section generally indicated by the numeral 25 10 inserted within the tubing 5, said section carrying the nozzle 9. This section 10 is connected to the tubing 5 at one end by means of the collar 11, while the other end of the section 10 is threaded into the sleeve 12 30 formed at the upper end of the hood 7.

In order that the gas may be caused to accumulate within the casing 1 and directed by means of the bell 7 into the tubing 5 whereby sufficient pressure will be utilized 35 to carry the oil up through the tubing 5 to the surface of the earth, a packing member 13 is mounted upon the tubing 5 and fitted within the casing 1 so as to entirely fill the same and prevent any of the gas 40 from passing upwardly through the casing 1, unless the occasion should require. This packing member 13 is supported in its proper position, preferably at a point above the hood 7, by means of a plate 14, which is 45 welded or otherwise secured to the tube 5, said plate being provided with a plurality of openings 15 arranged in arcuate form as illustrated in Figure 3, and further provided with a stop lug 16. Mounted upon the 50 plate 14 is a second plate 17 having a plurality of openings 18 arranged in arcuate form about the center of the plate and adapted to coincide with the openings 15 in the plate 14, although it will be apparent that 55 the openings in the plate 17 can be moved around out of alignment with the openings 15 to close the passage through these openings. The plate 17 is provided with an arcuate recess 19, in which the lug 16 is 60 arranged whereby the plate 14 can be turned half around so as to bring the openings 15 and 18 into alignment to open communication 65 between the casing 1 and a sleeve 20, which is arranged within the packing member 13, or the plate 14 can be moved a half

turn so that the openings 15 and 18 will be disposed upon opposite sides of the tube 5 to thus close any passageway between the two plates.

The sleeve 20 which is arranged within 70 the packing member 13 is of a slightly larger diameter than the tube 5 and in order to retain the packing member 13 in position, a washer 21 is mounted upon the sleeve 20 having a jam nut 22 arranged above the 75 washer and a lock nut 23 arranged above the jam nut, both of said nuts being threaded upon the sleeve 20 to retain the packing member 13 within its proper position within the casing 1. This packing member is preferably formed of rubber, leather or any suitable material provided with the proper amount of flexibility so that after the packing member has been placed in position within the casing 1, the jam nut 22 and the 80 lock nut 23 can be manipulated against the the end of the packing member causing the side walls of the same to be forced tightly against the inner wall of the casing whereby to prevent any escape of the gas pressure up through the casing. It will also be noted that when the valve plates 14 and 17 are arranged so that the openings therein are disposed upon opposite sides of the tube 5, the gas pressure will not be permitted to pass upwardly within the casing 1, but directed by means of the hood 7 into the small tube 5 so that the accumulation of pressure beneath the packing member 15 will be sufficient to carry the oil up through 95 the tube 5.

The sleeve 20 is securely retained in position by having the nuts 25 threaded upon the tube 5 and forced against a thrust bearing 26, thus preventing any upward movement on the part of the sleeve 20. The upper end of the tube 5 extends upwardly through the cap 2 and the suitable thrust bearing 27 is arranged above the cap 2 to permit rotation of the tube 5 and it will 105 be noted that upon rotation of the tube 5, the valve plate 14 will be rotated so as to move the openings 15 thereof into or out of alignment with the openings 18. It will be apparent that the plate 17 is welded or 110 otherwise secured to the sleeve 20 so as to retain the plate in the same relative position with respect to the packing member 13 so that when the tube 5 is rotated, thus imparting a rotary movement to the plate 115 14, the openings 15 and 18 will be moved into or out of alignment with each other, the lug 16 providing a stop for the movement of the plate 17, so that the plate 17 will not move beyond its proper position 120 to bring the openings 15 and 18 into alignment or move them out of alignment. I further wish to emphasize the fact that while I have shown and described a plurality of openings 15 formed in the two 125 130

valve plates, a single opening or any number of openings may be used if desired, according to the pressure of gas in the well in which my device is to be used.

5 In the operation of my device, the tubing 5 carrying the hood 7 and the packing member 13 in its assembled position as shown in Figure 1, is lowered into the casing 1 to a point in or just above the lower end 10 of the casing, but the tube 5 may project below the bell 7 into the fluid to be removed from the well and extend on to the bottom of the well if desired and any number of 15 perforations 6 can be formed in the tube to permit the oil to pass into the tube. The tube 5 is then rotated until the passage 20 through the openings 15 and 18 is closed. The pressure of gas within the casing 1 then accumulates below the packing member 13 until the pressure is sufficient to raise the 25 oil through the tubing 5, the oil and gas entering the tube 5 through the hood 7 and the openings 8 in the tubing. Should the pressure of gas become so great that it will 30 cut the oil and it is desired to relieve the pressure within the tubing 5, the tube is rotated so as to open communication between the valve plates 14 and 17, bringing the openings 15 and 18 into alignment, the 35 gas pressure passing through these openings up through the sleeve 20 and out through the openings 28 formed in the upper end of the sleeve, said openings communicating with the casing 1 above the packing member 13, thus the gas pressure will be permitted 40 to pass upwardly by the packing member 13 and out through the outlet pipe 3. From this it will be apparent that the gas pressure can be readily relieved when 45 so desired and as soon as the pressure is back to its normal state, the tube 5 is rotated to close communication between the casing 1 below the packing member 13 and the sleeve 20 to thus again direct the gas pressure into the tube 5 within the hood 7.

If found desirable, a suitable outlet pipe 29 may be connected to the upper end of the tube 5 whereby the oil forced upwardly 50 through the tube by means of the accumulation of the gas pressure within the casing may be conveyed to any desirable place.

I wish it to be understood that while I have shown and described means for utilizing the remaining gas pressure within a 55 well, should this gas pressure become exhausted before the oil has been entirely drained from the well, or upon further accumulation of oil within the well, gas pressure may be forced into the casing, down 60 through the sleeve 20 and pass downwardly beyond the hood 7, its only means of escape being upwardly through the hood into the tube 5 through the openings 8 and from this it will be apparent that suitable suction 65 or pressure will be provided for drawing

the oil from the bottom of the well if the original supply of gaseous pressure has been exhausted from the well.

What I claim is:

1. In a fluid elevator, the combination 70 with a casing, of a tube arranged within the casing having a lower end constricted to admit the fluid to the tube, means for admitting gas pressure into the tubing above the openings, means for diverting the gas pressure toward the means of admission into the tubing, additional means arranged within the casing above the admission openings for preventing upward movement of the gas pressure in the casing and means for relieving 75 the gas pressure from the casing upon the accumulation of an excess pressure. 80

2. A device of the class described, including in combination with a casing, a tube arranged within the casing, said tube having 85 openings therein for the admission of fluid and gas pressure, means for directing the gas pressure into the openings provided therefor, a packing member arranged within the casing to prevent upward movement 90 of the gas pressure whereby to provide an accumulation of gas pressure for raising the fluid within the tube and means for relieving the pressure of gas upon the accumulation 95 of an excess pressure. 95

3. A device of the class described, including in combination with a casing, a tube arranged within the casing having openings in its lower end, a valve plate carried by the tube, a packing member arranged within the 100 casing above the valve plate, a sleeve surrounding the tube and arranged upon the interior of the packing member, a second valve plate carried by the sleeve and mounted upon the first valve plate, said valve 105 plates having corresponding openings therein whereby the turning movement of the tube will open or close said openings.

4. A device of the class described, including in combination with a casing, a tube arranged within the casing having openings in its lower end for the admission of fluid, said tube being also provided with additional openings, a hood surrounding the tube for directing the gaseous pressure 115 toward the additional openings and a nozzle arranged within the tube having a reduced mouth portion disposed adjacent the outlet of the additional openings whereby to create a pressure passing upwardly into the 120 tube and means for regulating the pressure of gas within the casing for raising the fluid within the tube.

5. A device of the class described, including in combination with a casing, a tube arranged within the casing having openings in its lower end, means carried by the tube for directing the gaseous pressure into the tube, a packing member arranged within the casing, a valve plate carried by the tube be- 125 130

neath the packing member and a sleeve arranged within the packing member and surrounding the tube, a second valve plate carried by the sleeve and co-operating with the 5 first valve plate whereby to open and close communication between the casing below the packing member and the sleeve, said sleeve being provided with outlet openings at its upper end whereby turning movement of 10 the tube will rotate one of the valve plates to open and close communication between the parts of the casing above and below the packing member.

6. A device of the class described, including in combination with a casing, a tube arranged within the casing, means admitting fluid and a gaseous pressure into the tube, a packing member arranged within the casing above said means, a valve plate carried by 20 the tube beneath the packing member, a sleeve arranged within the packing member and surrounding the tube, a second valve plate carried by the sleeve and cooperating with the first valve plate, said sleeve having 25 outlet openings at its upper end whereby turning movement of the tube will open or close communication between the parts of the casing located above and below the packing member to relieve an excess accumulation 30 of gas pressure below the packing member.

7. In a fluid elevator, the combination

with a casing, of a tube arranged within the casing having a liquid inlet, means arranged within said casing above the inlet to retain 35 gas pressure therein for forcing liquid into the tube through the inlet and manually operated means whereby to relieve the gas pressure from the casing upon accumulation of an excess pressure. 40

8. In a fluid elevator, the combination with a casing, of a tube arranged within the casing having inlet openings adjacent its lower end, means arranged within the casing whereby to create a gas pressure within 45 the casing for forcing the fluid through the inlet openings into the tube, means for directing the flow of fluid into said openings and means whereby to relieve the gas pressure from the casing upon accumulation of 50 an excess pressure.

9. In a device of the class described, the combination with a casing, of a tube arranged within the casing having a liquid inlet, said tube being provided with additional 55 openings, a hood surrounding the tube for directing the gaseous pressure toward the additional openings and a nozzle arranged within the tube having a reduced mouth portion disposed adjacent the outlet of the additional openings whereby to create a pressure passing upwardly into the tube. 60

In testimony whereof I affix my signature.
THOMAS P. CARSON.
